UNITED STATES PATENT OFFICE.

CHARLES SCHOENFELD, OF CANTON, OHIO.

LOCK.

1,121,047.

Specification of Letters Patent. Patented Dec. 15, 1914.

Application filed August 11, 1913. Serial No. 784,028.

To all whom it may concern:

Be it known that I, CHARLES SCHOENFELD, a citizen of the United States, residing at Canton, in the county of Stark and State of Ohio, have invented certain new and useful Improvements in Locks, of which the following is a specification.

My invention relates to improvements in locks, more especially to that class of locks used upon doors of houses, but is equally applicable to doors of jail or prison cells or the like and has for its object, to provide a lock of the class mentioned in which the bolt is held in positive locked position by the automatic action of devices so arranged that the bolt will be positively held in position to lock the door to any object to which the door proper may be attached.

A further object is to provide means for actuating the devices designed to hold the bolt in an outward position and to release the bolt.

These objects, together with other objects readily apparent to those skilled in the art I attain by the construction illustrated in the accompanying drawings.

In the accompanying drawings—Figure 1 is a plan view of my improved lock showing the parts thereof in normal position when the bolt is free to be withdrawn or moved inward. Fig. 2 is a view showing the different parts of the lock in normal position when the bolt is moved outward and locked against endwise movement, except by a key. Fig. 3 is a view of the lock casing showing the detachable parts removed. Fig. 4 is a view showing the lock bolt, its spring and the key actuated lever and the locking dog in normal position when the bolt is moved outward and locked. Fig. 5 is a perspective view of the sliding bolt locking plate and its bevel ended strike bar. Fig. 6 is a top edge view of the sliding bolt locking plate and its bevel ended strike bar. Fig. 7 is a front edge view of the lock.

Similar numerals of reference indicate corresponding parts in all the figures of the drawings.

The casing 1 is of the usual form and is provided with the usual connecting plate 2 and cover, all of which parts are common and do not enter into the present invention except that a casing and its usual parts must necessarily be present. The cover or top plate 2 is of the usual construction, and is not illustrated but is fitted to the casing 1

in the usual manner. The locking bolt 3 is provided with the enlarged head 4, said head having the beveled outer face 5 adapted to project into the keeper 6 when in locked position. The bolt 3 is located within the casing and is held by the bifurcated post 7 and the mortise or opening 8^a formed in the connecting plate 2. The bolt 3 is provided with the flange 8, which flange is for the purpose hereinafter described, and also for the purpose of providing a shoulder or abutment for one end of the spring 9, the opposite end of said spring being located against the collar 10, which collar is located against the face of the bifurcated post 7 as best illustrated in Figs. 1 and 2. The spring 9 is for the purpose of normally holding the bolt 3, together with its different parts in an extended or outward position.

To the casing 1 is attached in the usual manner the tumbler casing 11 which tumbler casing is provided with the usual tumblers, which are common and form no specific part of the present invention, but are of the usual key tumbler construction such as used in locks upon the market and hence no detailed description is necessary. For the purpose of preventing any accidental rotation or movement of the tumbler 11, said casing is provided with the notches 12 into one of which notches is normally seated the bar 13, which bar is held against end movement by means of the screw 14, which screw is located in a suitable screw threaded aperture formed in the head 15, so that by rotating the screw 14 in one direction will force the bar 13 into one of the notches 12 and by rotating the screw in the opposite direction will withdraw the bar 13 from one of the notches 12, after which the tumbler casing can be removed. It will be understood that the screw 14 has no longitudinal movement during the time it is rotated, the same being properly journaled in the post 16. The just above described parts are also common and form no specific part of the present invention, except that they or their equivalents must necessarily be present.

To the casing 1 is pivotally attached the bell or L shaped lever 17, the arm 18 of said lever being so located that it can be actuated by the key actuated bar or arm 19, which is moved by the key and when it is desired to move the bolt 3 so as to release it from its keeper, or in other words to unlock the door

the arm 19 is turned and brought into contact with the arm 18, the arm of the bell shaped lever 17 being pressed downward which in turn rocks the bell or L shaped lever 17 upon its pivotal point, thereby moving the upward or vertical arm 20 inward, which action moves the locking bolt 3 inward by reason of the short flange or rib 21 striking against the outer face of the flange 8.

For the purpose of normally holding the arm 18 in an upward position and the arm 20 in an outward position, the leaf spring 22 is provided, which spring is connected to the casing 1 and its free end pressing against the under side of the arm 18, by which arrangement the arm 20 will follow the movement of the bolt 3 when it is forced outward or into position to lock the door.

It is quite well understood that locks in which the bolts can be forced backward may be opened by bringing pressure upon the beveled face of the locking bolt normally located in the keeper, the usual method being to insert a flat piece of metal between the lock proper and the door casing and gradually forcing the locking bolt out of its keeper, thereby unlocking the door without the use of a key. In order to prevent the picking of a lock it is necessary to provide means for locking the locking bolt against end movement or in other words locking the locking bolt in an outward position and in such a manner that the extended or beveled end can not be forced backward except by the use of a key or other instrument intended to actuate the locking bolt.

For the purpose of locking the locking bolt 3 in its outward position independent of the key, I provide a sliding plate 23, which sliding plate is provided with the beveled head or end 24, which beveled end strikes the door jamb when the door is closed, thereby moving the locking plate 23 inward, which locking plate is connected to the lock casing by means of the pin or screw 25, which is located through the elongated slot 26 formed in the sliding plate 23.

To the casing 1 is pivotally attached the latch or locking bar 27, which latch bar is held up by reason of the pin 28 carried by the sliding plate 23 coming in contact with the shoulder 29; but when the pin 28 is moved from under the shoulder 29, the latch bar 27 is free to drop into the position shown in Fig. 2 and when in that position the outer or free end of the catch bar 27 drops back of the shoulder 30, thereby, preventing any end movement of the locking bolt 3 except when actuated by the key designed to actuate the lock proper.

It will be understood that when the bevel ended head 24 is pressed inward, the latch 27 will be released and permitted to fall, and the locking bolt 3 held in the keeper by

reason of the latch plate 27 and in such a manner that it cannot be moved by any pressure brought against the beveled face of the locking bolt 3.

When it is desired to unlock the door or in other words move the locking bolt 3 endwise the arm 19 is moved by the key and the bell crank or lever 17 rocked thereby moving the vertical arm 20 inward at which time the top or upper end of the arm 20 strikes the beveled faced lug 31 formed upon the latch bar 27, thereby lifting the latch bar 27 and releasing the same from the shoulder 30, at which time the locking bolt 3 is free to be moved endwise by the arm 20, the rib 21 coming in contact with the flange 8, it will be understood that before the locking bolt 3 can be moved endwise the latch bar 27 must be first lifted and in order to first lift the latch bar 27 the rib 21 should be normally spaced a short distance from the face of the flange 8, so that by the time the rib 21 reaches the flange 8 the latch bar 27 will be lifted out of engagement with said flange 8.

In order to insure the dropping of the latch bar 27 when the sliding plate 23 has been moved inward the spring 32 is provided, which spring is held in tension by inserting its free end under the pin 33 and seating the opposite end of the spring in a notch or a recess 34 formed in the latch bar 27. For the purpose of moving the sliding plate 23 in an outward direction so as to extend the beveled end 24 beyond the plate 2, the spring 34 is provided, one end of said spring being attached to the face plate 2 or its equivalent and the opposite end being attached to the pin 28 or its equivalent.

It will be understood that the extreme top of the arm 20 of the bell shaped lever 17 should be beveled so that as the arm moves inward the beveled flange 31 will ride upward upon the beveled end 35.

For the purpose of preventing the lock bolt 3 from being locked in an extended position during the time the door is being closed or at any other time when it is not intended to lock the lock bolt, against inward movement the beveled faced head 4 is so arranged with reference to the beveled head or end 24 located upon the sliding plate 23 that when the jamb of the door or other object comes in contact with the beveled face 5 of the head 4, the bolt 3 will be moved inward in advance of the inward movement of the beveled head 24 so that the latch plate cannot fall into position to lock the lock bolt 3 until after said lock bolt has been extended into its keeper, but after said lock bolt has been extended into its keeper the latch plate is free to fall and lock the bolt against endwise movement. The relative arrangement of the beveled heads 4 and 24 are clearly shown in Fig. 7, and as shown the striking face of the beveled head 4 is extended be-

yond or to one side of the head 24 a sufficient distance to move the lock bolt 3 before the latch plate 23 is actuated or in other words a portion of the beveled faced head 4 is located out of alinement with the beveled head 24.

Having fully described my invention what I claim as new and desire to secure by Letters Patent, is—

- 10 1. In a lock of the class described, a casing, a lock bolt carried within said casing, said lock bolt provided with a beveled faced head and a flange spaced from said head, an L-shaped lever pivotally connected to the casing, one of the arms of said lever being adapted to be actuated by the lock mechanism and the other arm of said lever located between the beveled faced head and the spaced flange, said arm provided with an extended rib and a beveled upper end, a spring controlled latch bar pivotally attached to the casing and said latch bar adapted for contact with the arm located between the head and flange of the lock bolt, 20 said arm provided with a shoulder, a sliding plate provided with a beveled end, and a pin adapted for engagement with the shoulder on said latch arm.
- 15 2. In a lock of the class described, a casing, a lock bolt carried within said casing, said lock bolt provided with a beveled faced head, and a flange spaced from said head, an L-shaped lever pivotally connected to the casing, one of the arms of said lever adapted to be actuated by the lock mechanism and the other arm of said lever located between the beveled faced head and the spaced flange, 25 said arm provided with a shoulder, a sliding plate provided with a beveled end, and a pin adapted for engagement with the shoulder on said latch arm.
- 20 3. In a lock of the class described, a casing, a lock bolt carried within said casing, said lock bolt provided with a beveled faced head, and a flange spaced from said head, an L-shaped lever pivotally connected to the casing, one of the arms of said lever adapted to be actuated by the lock mechanism and the other arm of said lever located between the beveled faced head and flange of the lock bolt, 30 said arm provided with a beveled upper end, a spring controlled latch arm pivotally attached to the casing and said latch arm adapted for contact with the arm located between the head and flange of the lock bolt, 35 said latch arm provided with a shoulder, and a sliding plate provided with a beveled end, and a pin adapted for engagement with the shoulder on said latch arm, the beveled head of the latch arm and the beveled head of the 40 sliding plate located in different planes with reference to the casing.

In testimony that I claim the above, I have hereunto subscribed my name in the presence of two witnesses.

CHARLES SCHOENFELD.
